UNITED STATES PATENT OFFICE.

SAMUEL A. NEIDICH, OF EDGEWATER PARK, NEW JERSEY, ASSIGNOR TO THE AMERICAN MULTIGRAPH COMPANY, OF CLEVELAND, OHIO, A CORPORATION OF OHIO.

INKING APPARATUS.

1,088,717.

Specification of Letters Patent.

Patented Mar. 3, 1914.

Original application filed September 28, 1910, Serial No. 584,202. Divided and this application filed September 8, 1911. Serial No. 648,324.

To all whom it may concern:

Be it known that I, SAMUEL A. NEIDICH, of Edgewater Park, in the State of New Jersey, have invented a certain new and useful Improvement in Inking Apparatus, whereof the following is a specification, reference being had to the accompanying drawings.

This application is a division of application Serial #584,202 filed September 28, 1910, for Letters Patent of the United States for improvement in duplicating machines.

My invention relates to machines adapted for printing impressions having the appearance of being manually typewritten, and may be employed with particular advantage in making assimilated printed and typewritten work in accordance with the process described in Letters Patent of the United States #640,013, granted to me December 26th, 1899.

As hereinafter described, my invention is embodied in a machine comprising a rotary printing drum and a coöperative rotary platen. Said drum is adapted to print from type set in a flexible chase detachably held on said drum, and, the ink for the printed impression is derived from a transfer sheet of textile fabric which is detachably held stationary on said drum over the type faces. Said sheet is supplied with ink for each impression by mechanism including a series of rollers interposed between said drum and an ink fountain, the terminal transfer roller being presented against said sheet and the other rollers coöperating to intermittently withdraw a definite, adjustably variable amount of ink from said fountain and deposit it upon said transfer roller.

My invention includes the various novel features of construction and arrangement hereinafter more definitely specified.

In the drawings:—Figure I is an elevation of the left hand side of a duplicating machine embodying my invention. Fig. II is a fragmentary elevation of the right hand side of said machine. Fig. III is a fragmentary vertical sectional view, taken on the line III, III in Figs. IV and V. Fig. IV is a fragmentary plan view of that portion of said machine shown at the left hand side of Fig. I. Fig. V is a vertical sectional view, taken on the line V, V in Figs. I, II,

III and IV. Fig. VI is an end view of the ratchet clutch mechanism for intermittently rotating the inking rollers. Fig. VII is a fragmentary plan sectional view of said clutch mechanism.

In said figures; the duplicating machine frame 1 supports the rotary printing drum 8, having at one end of its shaft the operating handle 12. Said drum 8 carries type 25 and is provided with means to detachably hold stretched over said type in stationary relation therewith, the ink transfer sheet of textile fabric 50 shown in Fig. III. Either said ink transfer sheet 50 or the type 25 may be reinked after each printing impression by the mechanism mounted in the carriage 63 under the removable cover 64 normally retained by the thumb screws 65. Said carriage being fitted to slide in the bearings 66 on said frame indicated in Fig. V, is conveniently shifted toward and away from said drum 8 by the shaft 67 which as 75 shown in Fig. III has the bearing blocks 68 arranged to slide in the carriage flanges 69, and the eccentrics 70 journaled in the bearings 71 in said frame. Said shaft 67 may be turned by the handle 72 shown in 80 Figs. II and IV having at its free end the spring pressed plunger detent 73, to engage the sockets 74 and 75 in the plate 77 on said frame; the arrangement being such that when said handle 72 is raised said carriage 63 is shifted toward the drum 8, to operative position, and when said handle is lowered said carriage is shifted away from said drum, to inoperative position. Although the extent of the backward and forward movement of said carriage 63 is limited by the locations of said sockets 74 and 75; said handle 72 may be rotatably adjusted in connection with said shaft 67, having the crown clutch hub 79 fitted to 95 engage the crown clutch collar 80 pinned on said shaft; said handle being rigidly secured in adjusted relation with said shaft by the screw 81 shown in Figs. II and IV. Said inking mechanism comprises five rollers, including the rubber faced ink transfer roller 82 which when said handle 72 is upturned to the position shown in Figs. II and IV is presented against said transfer sheet 50 as shown in Fig. III, to transfer ink to said sheet. Said roller 82 has

the gear 84 engaging the gear 86 on the drum 8 so as to rotate with the latter, and is journaled on the shaft 83 having the eccentrics 85 journaled in said carriage 63. 5 Said shaft 83 is rotatably adjustable but is normally held stationary by the set screw 88. The other four rollers of the inking mechanism have means coöperating to intermittently withdraw a definite, adjustably variable amount of ink from the fountain 87 and deposit it on said transfer roller 82. As indicated in Figs. II and III said ink fountain 87 is detachably connected with said carriage 63 by the thumb screws 89 10 which extend through the brackets 90 on said carriage in engagement with said fountain; the latter being precisely located by the dowel pins 91 projecting from said brackets 90 into the socket plates 92 which 15 are rigidly secured in adjustable relation with said fountain by the screws 94 and 95 shown in Figs. III and IV. As shown in Figs. III and IV, the metal faced roller 97 has its shaft 98 journaled in immovable 20 bearings in said fountain, and, the rubber faced roller 100 has its shaft 101 journaled in the eccentric bearings 102 in said fountain. The supply of ink 103 in said fountain 87 is upheld between said rollers 97 and 25 100 as shown in Fig. III; said rollers being intermittently rotated in the direction of the arrows marked thereon to dispense said ink in a thin film on the surface of said roller 97 from which it is intermittently 30 doffed by the rubber faced doffer roller 104 which alternately contacts with said roller 97 and with the metal faced distributing roller 105 and applies the ink to the latter which is continuously rotated solely by contact with said transfer roller 82. Said 35 doffer roller 104 being loosely mounted upon its shaft 106 is only turned when in contact with said roller 97 or in contact with said distributing roller 105; said roller 104 being 40 turned more than five revolutions in the direction of the arrow marked thereon in Fig. III each time it contacts with the distributing roller 105 but being turned in the opposite direction a fraction of a revolution when in contact with said roller 97. Said 45 eccentric bearings 102 for said roller 100 have respective wing levers 108 arranged to be clamped in adjusted position by the screws 109 on said fountain 87, so 50 that, by turning said bearings, the axis of rotation of said roller 100 may be adjusted toward and away from said roller 97, to vary the pressure of contact of said rollers and thus vary the thickness of the film of 55 ink spread upon the dispensing roller 97; the lateral location and extent of said film of ink being limited by the adjustable gates 110 shown in Figs. III and IV. Said gates being wedge shaped are pressed between 60 said rollers 97 and 100 by the spring arms 65

111 on the cross heads 112 which are adjustable toward and away from each other and are secured in adjusted position by the thumb nuts 113 on the bolts 114 which extend through slots in said fountain 87.

As shown in Figs. I and IV the rubber faced ink spreading roller 100 has the gear wheel 116 on its shaft 101 engaging the gear wheel 117 on the shaft 98 of the metal faced ink dispensing roller 97, so that as said rollers are turned together in the direction of the arrows in Figs. III and IV, but at different speeds, the ink 103 is drawn down between them and spread on said roller 97 in a film the thickness and extent of which has been adjustably predetermined. Referring to Figs. I, IV, VI, VII: In order to effect said differential turning movement of said rollers, the shaft 98 of said roller 97 has the gear 119 engaging the ratchet clutch gear 120, which is intermittently turned by the crank head 121 having the pivoted, spring pressed pawl 122 engaging the ratchet 123 in said gear 120, so that the latter is turned in the direction of the arrow in Fig. VI whenever said head 121 is turned in that direction, but is released and remains stationary during reverse movement of said head. Said crank head 121 is fixed on one end of the shaft 106 of said doffer roller 104; both ends of said shaft being eccentric with respect to the central portion thereof upon which said roller 104 turns, so that as said shaft is rocked in its bearings 124 in the carriage 63 the axis of rotation of said roller 104 is shifted back and forth as above described. Said crank head 121 has the spring 125 shown in Fig. VII tending to turn it into the position where the adjustable stop screw 127 rests on the ledge 128 of the carriage 63 as shown in Fig. I, in which position said shaft 106 holds the roller 104 in contact with the distributing roller 105 so as to be rotated by the latter. However, said head 121 is intermittently rocked in the direction of the arrows shown in Fig. VI, by the pitman 130 shown in Fig. I having the slot 131 for the crank pin 132 on the crank 133. Said pin 132 has the block 134 to encounter the shoulder 135 on said pitman 130 to thrust the latter upwardly during part of the continuous rotary movement of said crank 133 which is carried by the shaft 137 journaled in the frame 1 and having the gear 138 shown in Fig. III, fixed thereon inside said frame. Said gear is continuously rotated by engagement with the gear 140 carried by the gear 141 journaled on the stationary stud shaft 142 in said frame; said gear 141 being engaged by the gear 143 on the shaft 144 which has the gear 145 engaging the gear 147 on the main driving shaft 148 which is journaled in both side members of the frame 1. Said shaft 144 has the worm 155 fixed 130

thereon as indicated in Fig. II engaging the worm gear 156 on the counter shaft 157 journaled in the bearings 158 on the right hand side member of said frame 1. Said shaft 157 has the wrist plate 160 with the crank pin 161 engaging the link 162 which at its opposite end is connected by the pivot pin 163 with the yoke 164 shown in Figs. III and V which is upheld by the screws 165 so as to slide freely on the cross bar 166 which is fixed in said frame 1. Said distributing roller 105 rotates freely between the upturned ends of said yoke 164 as shown in Figs. III and V, but is longitudinally reciprocated on its shaft 170 by said yoke; said shaft 170 being journaled in said carriage 63 as shown in Fig. V. Said shafts 83, 101 and 106 etc., are respectively provided with the normally stationary but rotatably adjustable eccentric bushings 85, 102 and 124 etc., so that said shafts may be adjusted in precise parallel relation with the axis of the printing drum 8, and, it may be observed that such construction not only simplifies and facilitates the primary assembling of the machine but affords means to compensate for wear of the respective shafts, bearings and rollers.

The mechanism above described may be used as follows: The type 25 being set in the desired form is attached to the drum 8, and covered with the ink transfer sheet 50 as shown in Fig. III. The ink gates 110 being spaced and set in accordance with the width and location of the desired impression, and ink of the proper color and consistency being stored between said rollers 97 and 100 as indicated in Fig. IV; the mechanism is rotated by the handle 12 to dispense a sufficient quantity of said ink upon the rollers 97, 104 and 105 to coat the transfer roller 82 with a film thereof sufficient to replace upon the transfer sheet 50 or type 25, after each impression, the amount of ink which is removed therefrom by each impression of the type form.

The inking mechanism above described may be rendered inoperative by turning the lever 72 in the direction of the arrow marked thereon in Fig. II to withdraw the carriage 63 of the inking mechanism to inoperative position without stopping the machine or interrupting the printing operation above described; said ink transfer sheet 50 being saturated with ink like the ribbon used on ordinary typewriting machines. However, if the ink for the printed impressions is solely derived from any textile fabric said impressions must be successively lighter because of the depletion of ink from said fabric, even though the latter be moved between successive impressions to present different regions thereof for such impressions. Therefore, the inking mechanism described is advantageous in that it is

capable of reinking said sheet 50 after each impression so as to maintain it uniformly inked throughout the operation of printing any desired number of impressions; for instance, several thousand impressions may be made of uniform appearance during one continuous operation of the machine.

I do not desire to limit myself to the employment of any fabric on the drum 8, to receive the ink for the printed impressions as the faces of the type 25 may be directly inked by the roller 82, said sheet 50 being employed to produce impressions resembling typewriting. Therefore, I do not desire to limit myself to the precise details of construction and arrangement above described as it is obvious that various modifications may be made therein without departing from the essential features of my invention as defined in the appended claims.

I claim:—

1. The combination with a rotary type carrying drum; of an ink fountain; a series of inking rollers interposed between said drum and said fountain including a transfer roller presented next to said drum, and four other rollers provided with means cooperating to intermittently withdraw a definite, adjustably variable amount of ink from said fountain and deposit it upon said transfer roller, including a metal faced distributing roller in contact with said transfer roller; a rubber faced roller in said fountain; a metal faced roller in said fountain in contact with said rubber faced roller; a rubber faced doffer roller exterior to said fountain arranged to intermittently alternately contact with said metal faced fountain roller and said distributing roller; means arranged to intermittently rotate said doffer roller and shift the axis thereof to bring said roller alternately into contact with said metal faced fountain roller and said distributing roller; means arranged to axially reciprocate said distributing roller; gearing connecting said drum and said transfer roller arranged to continuously rotate the latter; and, means arranged to intermittently rotate said two fountain rollers.

2. The combination with a rotary type carrying drum; of an ink fountain; a series of inking rollers interposed between said drum and said fountain including a transfer roller presented next to said drum, and four other rollers provided with means cooperating to intermittently withdraw a definite, adjustably variable amount of ink from said fountain and deposit it upon said transfer roller, including a metal faced distributing roller in contact with said transfer roller; a rubber faced roller in said fountain; a metal faced roller in said fountain in contact with said rubber faced roller; a rubber faced doffer roller exterior

to said fountain arranged to intermittently alternately contact with said metal faced fountain roller and said distributing roller; means arranged to rotate said doffer roller and shift the axis thereof to bring said roller alternately into contact with said metal faced fountain roller and said distributing roller; means arranged to axially reciprocate said distributing roller; gearing connecting said drum and said transfer roller arranged to continuously rotate the latter; and, means arranged to rotate said two fountain rollers.

3. The combination with a frame; of a printing couple including a rotary drum having a shaft journaled in said frame; a carriage arranged to slide on said frame toward and away from said drum; a shaft having bearing blocks arranged to slide in flanges on said carriage, and eccentrics journaled in said frame; a handle on said shaft having a spring pressed plunger detent arranged to engage sockets on said frame; whereby when said handle is turned in one direction said carriage is shifted toward said drum and held in operative position and when said handle is turned in the opposite direction said carriage is shifted away from said drum and held in inoperative position; means on said handle whereby it may be rotatably adjusted in connection with said shaft, including a crown clutch hub fitted to engage a crown clutch collar on said shaft; means whereby said handle may be rigidly secured in adjusted relation with said shaft; an ink fountain detachably connected with said carriage by screws extending through brackets on said carriage; means precisely locating said fountain with respect to said carriage, including socket plates on said fountain; screws respectively adapted to shift and to secure said plates in rigid relation with said fountain; and, dowel pins projecting from said brackets into said socket plates.

4. The combination with a frame; of a printing couple including a rotary drum having a shaft journaled in said frame; a carriage arranged to slide on said frame toward and away from said drum; a shaft having bearing blocks arranged to slide in flanges on said carriage, and eccentrics journaled in said frame; a handle on said shaft having a spring pressed plunger detent arranged to engage sockets in a plate on said frame; whereby when said handle is turned in one direction said carriage is shifted toward said drum and held in operative position and when said handle is turned in the opposite direction said carriage is shifted away from said drum and held in inoperative position; means on said handle whereby it may be rotatably adjusted in connection with said shaft including a crown clutch hub fitted to engage a crown clutch collar

on said shaft; and, means whereby said handle may be rigidly secured in adjusted relation with said shaft.

5. The combination with a frame; of a printing couple including a rotary drum 70 having a shaft journaled in said frame; a carriage arranged to slide on said frame toward and away from said drum; a shaft having bearing blocks arranged to slide in flanges on said carriage, and eccentrics 75 journaled in said frame; a handle on said shaft having a detent, whereby when said handle is turned in one direction said carriage is shifted toward said drum and held in operative position and when said handle is turned in the opposite direction said carriage is shifted away from said drum and held in inoperative position; means on said handle whereby it may be rotatably adjusted 80 in connection with said shaft including a crown clutch hub fitted to engage a crown clutch collar in said shaft; and, means whereby said handle may be rigidly secured in adjusted relation with said shaft.

6. The combination with a frame; of a printing couple including a rotary drum having a shaft journaled in said frame; a carriage arranged to slide on said frame toward and away from said drum; an eccentric shaft journaled in said frame and having bearing blocks arranged to slide in flanges on said carriage, and, a handle on said shaft having a detent, whereby when said handle is turned in one direction said carriage is shifted toward said drum and held in operative position and when said handle is turned in the opposite direction said carriage is shifted away from said drum and held in inoperative position.

7. The combination, with a printing couple, of a carriage movable toward or from the couple, inking mechanism mounted on the carriage and including a distributing roller and a coacting transfer roller adapted to convey ink from the distributing roller 105 to the couple, means arranged to axially reciprocate said distributing roller, including a yoke transversely slidable on the carriage, a link connected with said yoke, and a crank mounted independently of the carriage and 110 connected with said link, means arranged to rotate said crank, and means to move the carriage toward and from the couple.

8. The combination, with a printing couple, of a shiftable carriage, a form roller 120 mounted thereon adapted to coact with the form on the couple, two coacting fountain rolls on the carriage adapted to uphold between them a supply of ink, means for conveying ink from one of the fountain rolls 125 to said form roll, a transverse bar on the carriage, two cross heads slidable on said bar and adjustably clamped thereto, leaf springs projecting from the cross heads over the fountain rolls, and V-shaped end gates seat- 130

ing on the fountain rolls and loosely connected with said springs respectively.

9. The combination of a rotary type carrying drum, a fabric held over the type thereon, a transfer roller positioned to bear against said fabric when the latter is backed by the type, means for carrying an ink supply, means for transferring ink from such supply to the transfer roller, a carriage in which the transfer roller, ink supply and transferring means are mounted, and means for adjusting the carriage toward and from the drum.

10. In a device of the character described, the combination, with a rotary printing couple, of a carriage, means for shifting the same toward and from the couple, an inking system mounted in the carriage and including two fountain rollers coacting to uphold the ink supply, the fountain roller nearest the printing member being of metal and the other having a rubber face, a longitudinally shiftable metal distributor roller, a rubber-faced ductor roller movable back and forth between the metal fountain roller and the distributor roller, and a rubber transfer roller acting against the distributor roller and adapted to convey ink to the printing couple.

11. The combination of a rotary printing drum, a transfer fabric stationarily carried thereby over the face of the type, an inking system adapted to automatically reink the fabric consequent upon the rotation of the drum, said system including a transfer roller adapted to bear against the fabric when backed by the type, two fountain rollers adapted to uphold the ink supply, and ductor and distributing rollers between one of the fountain rollers and the transfer roller.

12. The combination of a rotary printing

drum, a transfer fabric stationarily carried thereby over the face of the type, an inking system adapted to automatically reink the fabric consequent upon the rotation of the drum, a carriage movable toward or from the type carrying drum, two fountain rollers in said carriage adapted to uphold the ink supply, a transfer roller in said carriage adapted to contact with the fabric on the drum, a longitudinally movable distributor roller in the carriage coacting with the transfer roller, and a shiftable ductor roller in the carriage coacting alternately with the distributing roller and one of the fountain rollers.

13. The combination of a rotary printing drum, a transfer fabric stationarily carried thereby over the face of the type, an inking system adapted to automatically reink the fabric consequent upon the rotation of the drum, a carriage movable toward or from the type carrying drum, two fountain rollers in said carriage adapted to uphold the ink supply, a transfer roller in said carriage adapted to contact with the fabric on the drum, a longitudinally movable distributor roller in the carriage coacting with the transfer roller, a shiftable ductor roller in the carriage coacting alternately with the distributing roller and one of the fountain rollers, a gear on said drum, a gear on the transfer roller adapted to mesh therewith or be out of contact therewith according to the position of the carriage, and means for moving the carriage in and out.

In testimony whereof, I have hereunto signed my name at Burlington, New Jersey, this sixth day of September, 1911.

SAMUEL A. NEIDICH.
